Primary Examiner — Cynthia M Chin*(74) Attorney, Agent, or Firm* — John A. Kramer; Global Patent Operation(57) **CLAIM**

The ornamental design for a marine control panel, as shown and described.

DESCRIPTION

FIG. 1 is a perspective view of a marine control panel depicting our new design;
FIG. 2 is a top view thereof;
FIG. 3 is a side view thereof;
FIG. 4 is an opposite side view thereof;
FIG. 5 is a front view thereof; and,
FIG. 6 is a back view thereof.
The broken line portion of the figure drawings is included to show unclaimed subject matter only and forms no part of the claimed design.
